R. VACHIER

PROCESS FOR INCREASING SUGAR RECOVERY

Filed May 12, 1925

Patented Mar. 23, 1926.

1,578,220

UNITED STATES PATENT OFFICE.

RAFAEL VACHIER, OF BATON ROUGE, LOUISIANA.

PROCESS FOR INCREASING SUGAR RECOVERY.

Application filed May 12, 1925. Serial No. 29,750.

To all whom it may concern:

Be it known that I, RAFAEL VACHIER, a citizen of the United States, residing at Baton Rouge, in the parish of East Baton Rouge and State of Louisiana, have invented 5 certain new and useful Improvements in Processes for Increasing Sugar Recovery; and I do hereby declare the following to be a full, clear, and exact description of the invention, such as will enable others skilled in the art to which it appertains to make and use the same.

The present invention relates to a process of manufacturing cane sugar, and has for an 15 object to recover a greater percentage of the sugar during the process, and wherein is abolished the usual filter-press station considered essential.

Another object of the invention is to provide 20 a process for desugarizing the mud, which is produced by any of the well established processes of defecation or clarification in sugar manufacture in cane sugar factories and wherein no additional amount of water 25 is used than is consumed in the present practice.

Another object is to bring the mud to the lowest possible sucrose content previous to 30 its coming into contact with the water, which is to finally exhaust it, so that the mud after this final treatment is completely exhausted and may be sent to the fields as fertilizer.

Briefly stated, the improved process embodies 35 the taking of the thin juices from each one of the milling units or stages, separating them and then screening, adding lime to them separately, heating them and finally clarifying each separate product, so as to have a series of juices decreasing in density 40 and sucrose content. The decanted mud from each of the previous clarifiers is admixed with the inflowing juice of the subsequent clarifier, which juice is lower in sugar content than the liquid element of the mud. 45 The mud decanted from the first clarifier passes through the second and third clarifiers, which contain juices of inferior densities and sugar content and the mud is finally passed through a de-sugarizer where the 50 partially exhausted mud is brought into contact with the water intended for maceration on the last one or more stages of the milling process. Of course the mud may be passed in series through any number of stages of 55 the milling process according to the size of the mill and the clear juices from the clarifi-

fers may be sent directly therefrom to the evaporators, or they may be used as maceration in front of some of the mills.

With the foregoing and other objects in view, the invention will be more fully described hereinafter, and will be more particularly pointed out in the claims appended hereto.

In the drawing the single view shows, diagrammatically, a four stage milling plant 65 constructed to carry out the process according to this invention.

Referring to the drawing, 10 designates a pair of crusher rolls and from which the 70 cane is passed to the first mill 11. The thin juices extracted in the first mill are carried downwardly through a screen 12 to a heater 13 and a quantity of lime is added to the thin juices as they enter the heater. The 75 limed thin juices are then conducted to the clarifier 14 where the mixture is separated into a clear juice which is carried off through a pipe 15 to an evaporator or the like as 80 diagrammatically shown. The mud separated in the clarifier is conducted through pipe 16 to the heater 17 of the second mill or stage in the process. The second mill 18 delivers the thin juice to its screen 19 and thence to the heater 17, a quantity of lime 85 being added to this thin juice from the second mill. The mud from the pipe 16 or the first stage is here admixed with the second thin juice and lime, is heated and then conducted to the second clarifier 19. This second admixture is separated into a clear juice, 90 which is carried off through a pipe 20 to an evaporator or the like, and the mud which is carried off through the pipe 21 to the heater 22 of the third mill 23.

In a similar manner the third mill has a screen 24 through which the third thin juice is strained, after which it is limed and conducted to the heater 22, and finally to the third clarifier 25. The clear juice from the 100 third clarifier 25 is conducted through pipe 26 and delivered as maceration in front of the second mill 18, although this is optional. The mud from the third clarifier 25 is conducted through pipe 26 to a de-sugarizer 27 used for the final extraction of the sucrose content from the mud. The fourth mill or stage 28 delivers its thin juice through the screen 29 to a pipe 30 for conducting this 105 last thin juice as maceration to a point in advance of the third mill 23. This of course is an optional arrangement, as is also the 110

four stage mill as any number of stages may be employed.

The de-sugarizer 27 receives the mud from the third clarifier 25 and receives a quantity of lime for admixture therewith and with maceration water from pipe 31. The decanted and exhausted mud from the de-sugarizer 27 is carried off through pipe 32 and is practically completely de-sugared and may be used as fertilizer or the like, it having no further sucrose content. The clear sweet water which is separated out in the de-sugarizer is conducted through pipe 33. This clear sweet water carried off through pipe 33 is used as maceration in front of the fourth stage or mill 28 and obviates the necessity of applying an additional or extra amount of water as maceration in front of the various stages or mills during the process.

It will be seen that the only water added is in the de-sugarizer and that by this process the mud is consecutively reduced in sucrose content throughout the various stages of the mill, and is finally and practically completely exhausted of its sugar content by the water of maceration and lime, which is added in the de-sugarizer or in the last stage of the process. Even from the de-sugarizer, the clear sweet water is collected and made use of as maceration, so that there is practically no waste use of the water which is used during any stage of the process.

It is obvious that various changes and modifications may be made in the details of the process and structural arrangements of the above specifically described apparatus for practicing the process, without departing from the spirit of this invention, all of such changes and modifications being restricted only by the scope of the following claims.

What is claimed is:—

1. That process for desugaring the partially exhausted mud obtained as the resi-

due in the sugar recovery process and without the necessity for the filtering operation, which consists in subjecting the partially exhausted mud to fresh water and a quantity of lime sufficient to produce coagulation and extract the sugar content of the mud, thereby producing a clear sweet water as maceration water for use in the milling process and a substantially desugared mud.

2. That process for recovering sugar from cane without the necessity for filtering operation, which consists in separately extracting thin juices from different stages of a mill, separately treating said thin juices to clarify the same, conducting the mud in series through the clarifying stages to consecutively decrease the sucrose content of the mud, treating the partially exhausted mud from the last clarifying stage with fresh water and lime to completely decant and exhaust the mud and to produce a clear sweet water of maceration, carrying off the finally decanted and exhausted mud, and returning the clear sweet water of maceration back through the stages of the mill.

3. That process for recovering sugar from cane without the necessity for filtering operation, which consists in separately extracting thin juices from different stages of a mill, separately treating said thin juices to clarify the same, conducting the mud in series through the clarifying stages to consecutively decrease the sucrose content of the mud, and to produce a clear juice as maceration, conducting the clear juice from the clarifier of one milling stage back to the previous stage of the mill as maceration water, treating the partially exhausted mud from the last clarifying stage with fresh water and lime to completely decant and exhaust the mud and to produce a clear sweet water of maceration, carrying off the finally decanted and exhausted mud, and returning the clear sweet water of maceration back through the stages of the mill.

RAFAEL VACHER.
